FREDERICK BAUMGARTNER, OF BROOKLYN, NEW YORK.

Letters Patent No. 85,356, dated December 29, 1868; antedated December 17, 1868.

IMPROVEMENT IN DEVICE FOR OPERATING WINDOW-SASH.

The Schedule referred to in these Letters Patent and making part of the same.

To all whom it may concern:

Be it known that I, FREDERICK BAUMGARTNER, of the city of Brooklyn, in the county of Kings, and State of New York, have invented a new and improved Device for Raising Window-Sashes; and I do hereby declare that the following is a full, clear, and exact description of the same, reference being had to the annexed drawings, forming part of this specification, in which—

Figure 1 is a vertical transverse section of a window-frame, taken on the line $x-x$, fig. 2, showing my invention as applied to a window.

Figure 2 is a front sectional view of my invention, the section being taken on the line $y-y$, fig. 1.

Similar letters of reference indicate like parts in both figures.

My invention consists in the combination of a toothed wheel, perforated band, and device for holding the band closely up to said wheel, so that its teeth will always enter the perforations in said band, whereby I am enabled to produce a simple and efficient device for raising window-sashes, as will be presently more fully set forth.

A designates a metallic ribbon or belt, which is secured at or near each end to the edge of the window-sash, and which is perforated with holes, $a-a$, at certain distances apart, as shown clearly in figs. 1 and 2.

I will here remark, that as an equivalent for a metallic belt, a band of any suitable material, with or without perforations or eyelets, may be used.

B is a toothed wheel, which is axled in a box, C, which latter is secured in a recess made in the casing of the window.

The teeth b of this wheel B are placed at such distances apart that, as the said wheel revolves, they will pass into the holes $a-a$ in the belt A, as will be clearly understood by reference to fig. 1.

D is a spiral spring, which is arranged within the box C, and which, in the present instance, is held at its lower end, at or near the bottom of the said box, (refer to fig. 1,) and which has connected to its upper end a cord, e, which cord passes over a drum, d , or over an enlarged portion of the axle of the wheel B, as will be understood by reference to fig. 2. In this instance the spring is a compressed one, but if a distended one be used, the cord would be attached to the lower part, and the upper part be supported, and the operation would be the same, as is obvious.

E is a pawl, secured to a rod or shaft, f, which latter is journalled in the box C, so that one end of said rod will project through the window-casing far enough to be seized and turned with the hand, for the purpose

of disengaging the said pawl from the teeth of a wheel, e, or its equivalent, secured either to the wheel B, or on the axle d , when it is desired to raise the sash; and for the purpose of causing said pawl to engage properly with the teeth of the wheel e, I employ a flat spring, g, which bears against the lower end of said pawl, and keeps it engaged with the teeth of the wheel e.

For the purpose of the more securely keeping the band A pressed up to the wheel B, so that the teeth of the said wheel will always properly enter the holes $a-a$ in said band, I have shown a pin, h, passing through two arms, i i, between which pin and the side of the casing the band is placed, and, inasmuch as said band is flexible, there will be no hindrance to the raising of the sash, however much the same may shrink or swell.

It will be noticed from the above description, and by reference to the accompanying drawing, that in first adjusting the device to a window, it will be necessary to cause the teeth of the band A to engage with the wheel B at such position of the parts of the device that when the sash is down the spring will be stretched by the cord c being wound on the drum d —the sash being shown in fig. 1 as nearly completely lowered.

This being the condition of the parts, it is only necessary to disengage the pawl E from the teeth of the wheel e, when the tendency of the spring will be to resume its normal condition, and hence assist in elevating the window-sash.

It will be here noticed that when the pawl E is engaged with the teeth of the ratchet-wheel e, the wheel B cannot be turned in one direction, and hence the sash cannot be raised. This is the case, whatever may be the distance the sash is elevated.

It will be further noticed that the sash can be slid down without manipulating the shaft f, and that the operation of shoving it down winds the cord c on the drum d , and hence the device is always in an operative condition.

My invention provides a simple and efficient device for raising and locking window-sashes, and one which will always be in operative condition, whether the sash be shrunken or swollen.

What I claim as my invention, and desire to secure by Letters Patent, is—

The combination of the wheel B, band A, and device $h-i$, or its equivalent, arranged and operating substantially as and for the purposes herein set forth.

FREDERICK BAUMGARTNER.
